UNITED STATES PATENT OFFICE.

JULIO P. HERNANDEZ, OF ILOCILLO, PHILIPPINE ISLANDS.

FILE-BOX.

1,135,282.

Specification of Letters Patent. Patented Apr. 13, 1915.

Application filed June 10, 1914. Serial No. 844,268.

To all whom it may concern:

Be it known that I, JULIO P. HERNANDEZ, residing at Iloilo, in the Province of Iloilo, Philippine Islands, have invented new and useful Improvements in File-Boxes, of which the following is a specification.

This invention relates to file boxes, for use in filing away papers, etc., and particularly to file boxes of that type composed of 10 relatively movable sections, the front section being slidably engaged with the bottom of the box.

The object of the present invention is to provide a construction of equalizing connections 15 between the front and back sections of the box, whereby the front section will be guided in an accurate path and prevented from binding in its movements, the said connections also serving to hold the front 20 section so as to permit of its easy adjustment to retain the papers or documents in position.

A further object of the invention is to provide equalizing connections of the character described which are connected so as to also 25 serve as partitions, whereby different kinds or sets of paper may be held separated from each other.

The invention consists of the features of construction, combination and arrangement 30 of parts herein fully described and claimed, reference being had to the accompanying drawing in which:—

Figure 1 is a side view of a file box embodying my invention. Fig. 2 is a top plan 35 view of the same. Fig. 3 is a vertical transverse section.

Referring to the drawing, 1 designates the stationary bottom of the box, 2 the rigid rear wall of the box projecting upwardly 40 from the bottom 1, and 3 the movable or adjustable front wall of the box movably connected with the bottom 1 and adjustable with relation to the wall 2. In the present instance I have shown the front wall 3 provided with a guide member 4 which slidably 45 engages a suitable form of guide way 5 in the bottom 1. It is well known that file boxes of this type are open to objection, in that the movable section 3 is liable to tilt 50 out of an accurate path of movement, so that its guide member or portion binds in the guideway. Through rust, oxidation or other causes the guiding surfaces of the bot-

tom and front walls are also liable to bind and inhibit free movements of the front wall. 55

It is the object of my invention to provide an equalizing connection between the walls 2 and 3 whereby these objections are overcome.

The equalizing connections embodying my 60 invention consist of opposite sets of like lazy-tong levers 6 connecting the side portions of the walls 2 and 3 on opposite sides of the storage space of the box. These levers are pivoted to said walls 2 and 3 and 65 to each other so as to extend and contract in a direction longitudinally of the box, the upper terminal pivots 6^a being in the form of fixed pivots, while the lower terminal pivots 6^b slidably engage guide grooves 6^c in the 70 walls 2 and 3, the construction and arrangement being therefore such that the wall 3 will always be held parallel with the wall 2 and prevented from tilting or canting vertically or laterally, by which the guiding 75 portions 4 and 5 are always maintained in a proper relative relation for an easy and accurate adjustment of the wall 3 toward and from the wall 2, as binding of the parts is thus prevented and an easy, quick and 80 rapid adjustment of the wall 3 insured, while at the same time the lazy-tong equalizing connections serve to retain the papers or documents against lateral displacement.

As shown, the upper pivotal connections 7 85 between the lazy-tong levers extend across the space between the sets of levers and form common pivot members therefor, by which the two sets of levers are connected to move in exact accord with each other. These pivot 90 members, preferably in the form of rods, also serve as partitions by which different kinds or sets of papers may be divided from each other, as will be readily understood.

I claim:—

A file box including relatively movable 95 front and rear walls, a bottom composed of slidably connected guide members carried by the respective walls, sets of lazy-tong levers extending between the said front and rear walls at each side of the box, said levers having upper and lower pivotal connections, the terminal upper connections forming fixed pivots between said levers and the front and rear walls, and the lower connections having terminal pivot members slid- 100 105

ably engaging the front and rear walls, and the intermediate upper pivot members comprising rods extending across the box and forming common pivotal connections for the upper ends of the sets of levers and serving also to provide a series of transverse partitions.

In testimony whereof I affix my signature in presence of two witnesses.

JULIO P. HERNANDEZ.
